UNITED STATES PATENT OFFICE

RICHARD H. WHITEHEAD AND WILSON E. PORTER, OF NEW HAVEN, CONNECTICUT,
ASSIGNORS TO THE NEW HAVEN CLOCK CO., OF NEW HAVEN, CONNECTICUT, A CORPORATION

CLOCK

Application filed June 13, 1927. Serial No. 198,314.

Our invention relates to an improvement in clocks particularly designed for use as automobile clocks, but not so limited, the object being to provide a clock with simple, reliable, convenient and accessible setting-means constructed with particular reference to normally leaving the hour- and minute-hands free of any restraint therefrom, whereby the time-keeping qualities of the clock are preserved unimpaired and whereby when the minute-hand is engaged it may be freely turned in either direction without loss of motion and hence of time.

With these ends in view, our invention consists in a clock provided with setting-means centrally located in its crystal and having certain details of construction and combinations of parts as will be hereinafter described and particularly pointed out in the claim.

20 In the accompanying drawings:

Fig. 1 is a view in front elevation of a clock embodying our invention;

Fig. 2 is a view thereof in side elevation;

Fig. 3 is an enlarged view thereof, partly in vertical central section and partly in elevation;

Fig. 4 is a detached broken perspective view of the minute-hand;

Fig. 5 is a detached perspective view showing the setting-spindle;

Fig. 6 is a corresponding view of the bearing-bushing; and

Fig. 7 is a corresponding view of the retaining-washer.

35 For the illustration of our invention, we have shown it as embodied in an automobile clock, though its use is not so limited. For the description of our invention, it is sufficient to say that the clock 10 is provided with a 40 bezel 11, a crystal 12 mounted therein, an hour-hand 13, a minute-hand 14, a dial 15, a center-arbor 16, and a sleeve 17 carrying the hour-hand 13. The features referred to may be of any approved construction and are the 45 usual features to be found in clocks, save that the minute-hand is provided upon the outer face of its rounded inner end with a concentric disk-like clutch-member 18 swaged to it, as shown in Fig. 3, and having a central- 50 opening 19 fitting with a drive fit over the

outer end of the center-arbor 16. The said clutch-member 18 is formed in its outer face with two coupling-grooves 20 located at right angles with respect to each other. Either of these grooves is adapted to receive a coupling- 55 rib 21 projecting from the inner face of a disk-like clutch-member 22, complementary to the clutch-member 18 and formed upon the inner end of a rotary and reciprocating setting-spindle 23, the outer end of which 60 is shouldered for the reception of a knurled finger-button 24, over which the extreme outer end of the said spindle is swaged, as shown in Fig. 3. The said spindle is mounted in a bushing 25 shouldered to form a sleeve 26 65 passing outwardly through a hole 27 in the crystal 12 and through a hole 28 in the center of a retaining-washer 29 bearing directly upon the outer face of the crystal 12, the outer end of the sleeve 26 being swaged, as 70 shown in Fig. 3, over the outer face of the washer, whereby the bushing 25, in which the spindle is free to rotate and reciprocate, is permanently secured in the crystal 12.

To normally maintain the coupling-rib 21 75 out of engagement with the coupling-grooves 20, we employ a helical retracting-spring 30 encircling the outer end of the said spindle 23 and interposed between the outer end of the sleeve 26 and the underface of the knurled 80 finger-button 24.

To set or re-set a clock embodying our invention, it is only necessary to press directly inward upon the finger-button 24 with sufficient pressure to overcome the tension of the 85 spring 30. The button is then slightly rotated in one direction or the other until the coupling-rib 21 has been introduced into one or the other of the coupling-grooves 20, whereby the clutch-members 18 and 22 are 90 joined, thus bringing the minute- and hour- hands under the control of the knurled finger- button 24, which is now rotated in one direction or the other as required for setting the hands. The moment the pressure of the 95 fingers is removed from the finger-button 24, the helical retracting-spring 30 asserts itself to retract the setting-spindle and so disengage the clutch-member 22 from the clutch- member 18. The spindle is thereafter main- 100

tained in its retired position by the retracting-spring until it is again pressed inward by the intentional effort of the user of the clock.

5 Under the construction described, the setting-mechanism is normally disengaged from the minute-hand and therefore imposes no restraint whatever upon the running of the clock, the time-keeping qualities of which are therefore unaffected by the presence of the means for setting. At the same time, the setting-mechanism is of such a character that it does not permit the access of dust into the clock, and is so located as to afford the ultimate convenience for the setting of the same. Moreover, the construction of our improved setting-means is such that its accidental operation and the consequent disturbance of the hour- and minute-hands is so remote as to be negligible.

20 We claim:

In a clock, the combination with the center-arbor, hands and crystal thereof, of setting-means installed in the crystal in line with the center-arbor, and normally-separated clutch-members having symmetrically-arranged contacting portions, said clutch-members being interposed between the said setting-means and the outermost of the hands and respectively carried by the center-arbor and the setting-means, the clutch-member carried by the center-arbor being located in front of the plane of the outermost hand, whereby the fouling of the outermost hand by the inter-engagement of the clutch-members is avoided.

25 In testimony whereof, we have signed this specification.

30 RICHARD H. WHITEHEAD.

WILSON E. PORTER.
